UNITED STATES PATENT OFFICE.

HENRY RASQUIN, OF NEW YORK, N. Y.

SKATE-FASTENING.

Specification of Letters Patent No. 26,783, dated January 10, 1860.

To all whom it may concern:

Be it known that I, HENRY RASQUIN, of the city, county, and State of New York, have invented a new and useful Improvement in Skating-Boots; and I do hereby declare that the following is a full and exact description thereof, reference being had to the annexed drawings, making part of this specification, in which—

10 Figure 1, is a vertical section of the boot and the skating iron; Fig. 2, a perspective view of the skating iron; Fig. 3, a horizontal view of the sole and heel of the boot; Fig. 4, a vertical longitudinal section of the 15 spring box.

Similar letters of reference indicate corresponding parts in these figures.

The nature of my invention consists in so constructing the lower part of the boot 20 and the skating iron that they may be attached to each other without tying, buckling, or strapping.

To enable others skilled in the art to make and use my invention I will proceed to 25 scribe it.

The skating iron consists of a horizontal heel plate *a* and vertical runner *C*. The latter is provided with two pins or wedges *E* and *E'* fitting into small metallic boxes 30 *H* and *K* of the boot. One of these boxes is inserted in the heel *B* and the other in the toe. In the center of the sole there is a groove *F* in which the vertical runner *C* fits.

35 The boxes, one of which is represented in

Fig. 4, contain each a spring *e*, which consists of a plate turned upward on the mouth of the box in such a manner as to keep the box closed when the skating iron is removed from the boot.

40 When the pin *E* or *E'* is wedged into the box the spring plate *e* is lifted upward into the position shown by the dotted lines in Fig. 4 and the pressure of the spring will assist in keeping the said pin or wedge in 45 its position in the box.

The skating iron is fastened to the boot by shoving the same into the groove *F* and by forcing the wedges *E* and *E'* into their respective boxes *H* and *K*. The skating 50 iron of each boot is therefore supported and fastened on three points, which is sufficient for the steadiness of the same during skating.

This construction will obviate the use of 55 bands, buckles, or springs for the purpose of securing the skating iron to the boot.

What I claim as new and desire to secure by Letters Patent is—

1. Providing the skating iron with two 60 pins or wedges substantially as described.
2. Providing the boot or shoe with a groove *F* and with spring boxes *H* and *K* substantially as described and for the purpose set forth.

Dated New York October 17, 1859.

HENRY RASQUIN.
